TRAVELING CRANE

Peer D. Nielsen, Lorain, Ohio, assignor to National Tube Company, a corporation of New Jersey

Application May 17, 1939, Serial No. 274,270

1 Claim. (Cl. 212—21)

This invention relates to overhead traveling cranes carrying two electrically powered trolleys, such as a hook trolley and a bucket trolley. One of the objects is to provide for the individual operation of these trolleys without necessitating the crane operator leaving his cab and throwing switches on the trolleys.

A specific example of the invention is illustrated by the accompanying drawing, in which:

10 Figure 1 is a side view of the bridge of an overhead traveling crane incorporating the invention; and,

15 Figure 2 is a wiring diagram illustrating the principles of the invention.

20 More specifically, the drawing illustrates the tracks 1 over which the crane bridge 2 transversely travels, this bridge consisting of spaced girders carrying trolley tracks 3 forming a trackway for a bucket trolley 4 and a hook trolley 5, respectively, powered to travel over the trolley trackway, by motors 6 and 7.

25 One of the girders of the bridge 2 longitudinally carries electric conductor bars 8, each of the trolleys 4 and 5 carrying staffs 9 and 10, respectively, mounting electric collector shoes 11 and 12 which slide over the bars 8. The shoes 11 and 12, respectively, connect with the motors 6 and 7, whereby energization of the bars 8 energizes the trolley motors. A crane operator's 30 cab 13 is suspended from one end of the bridge 2, and suitable electrical controls are centralized in this cab for the convenience of the operator, these controls including a control system for electrically energizing the bars 8 to power the motors 35 6 and 7.

It is undesirable to operate both of the trolleys at once, and it is the prior art practice to provide manually operated switches on each of the trolleys for disconnecting their motors from 40 their collector shoes. The use of these switches enables either one or the other of the trolleys to be operated, but their operation necessitates the crane operator leaving his cab 13 and climbing on the crane bridge walkway. This exposes him to danger and is a generally unsatisfactory procedure.

45 According to the present invention, opposite end portions 8^a and 8^b of the bars 8 are segregated from the portion 8^c therebetween. The portions 8^a and 8^b are as short as they can possibly be made and still enable the adjacent trolley to be run to a position where its collector shoes 7 slide onto the segregated portions. The 50 segregation is accomplished by interposing in-

sulators 14 between the segregated and main portions of the bars 8.

Furthermore, the trolley control system is provided with switches operable from the cab 13 for selectively energizing either of the end portions 8^a or 8^b and the main portion 8^c without simultaneously energizing both of the end portions 8^a and 8^b. With this arrangement, the operator can run the trolley that he does not desire to use to the adjacent end portion of its 10 trackway, this bringing its collector shoes onto the segregated end portion of the bars 8. Then, by deenergizing this end portion and energizing the other end portion and the central portion 8^c of the bars 8, control of the other trolley is possible without energizing the motor of the trolley run to the end of its trackway.

15 A suitable circuit for accomplishing the above is illustrated by Figure 2 as consisting of a four-pole, double-throw safety switch 15 adapted to connect power lines 16, which are connected to the portion 8^c of the conductor bars 8, to either of the end portions 8^a or 8^b by way of lines 17 and 18, respectively. The switch 15 is of the type having interlocked switching elements which 20 positively prevent energization of the lines 17 and 18 at the same time, this switch 15 being located in the cab 13 for the convenience of the crane operator.

25 The reason there are four of the conductor bars 30 8 is because two of them directly energize the armatures 6^a and 7^a of the motors 6 and 7, while the other two energize the series fields 6^b and 7^b of these motors, whereby proper connections through the control equipment located in the cab 35 13, permit reversing operation of the trolley motors in the conventional manner.

35 I claim:

A crane including a transversely travelling bridge, a trolley trackway longitudinally carried by said bridge, at least two trolleys traveling said trackway, electric motors carried by said trolleys for powering the same to travel over said trackway, electric conductor bars extending longitudinally of said bridge, electric collecting elements carried by said trolleys and slidingly contacting said bars, said elements electrically connecting with said motors so that electric energization of said bars powers said motors, a crane operator's cab carried by said bridge and electric control equipment centralized in said cab for the convenience of the crane operator and including a control system for electrically energizing said bars to power said motors, said bars having opposite end portions electrically in- 45 50 55

sulated from their portions therebetween and said control system having means for selectively effecting electric energization of either one or the other of said end portions and said portion therebetween, whereby the crane operator can selectively energize the driving motor of either one of

said trolleys without simultaneously energizing the other, by positioning the other trolley so its collector element slides to one or the other of the insulated end portions of said bars.

PEER D. NIELSEN.
